DESIGN FOR A STORE

James F. Speck, Altus, Okla.

Application August 7, 1935, Serial No. 58,004

Term of patent 7 years

To all whom it may concern:

Be it known that I, James F. Speck, a citizen of the United States of America, residing at Altus, in the county of Jackson and State of Oklahoma, have invented a new, original, and ornamental Design for a Store, of which the following is a specification, reference being had to the accompanying drawing, forming a part thereof.

In the drawing

Figure 1 is an external view in perspective of a store, showing my new design, it being understood that the other side of the store is substan-

tially the same as that disclosed and that the store has a plain back.

Figure 2 is a perspective view of the interior of the store looking from the front toward the rear and discloses the predominating features of the design, a portion of the screen at the left being broken away to show more clearly the wall portion of the design.

I claim:

The ornamental design for a store, as shown and described.
